WALL PLATE

Edward William Martin, Roxbury, Conn.

Application September 16, 1944, Serial No. 554,489.

8 Claims. (Cl. 108—1)

This invention relates to building construction and more particularly to means for securing roof rafters, ceiling joists and gutters to the walls of buildings. According to my invention these means include a wall-plate that is secured to the top of the building wall and takes the place of the usual wooden wall- or frame-plate for receiving the roof rafters, as will be more fully described herein below.

There is a considerable demand for simplifying the construction of buildings in order to save labor costs. The tendency in recent years has been to increase the use of prefabricated parts which can be readily installed. One of the most tedious and complicated operations in ordinary building construction is the usual method of securing roof rafters, ceiling joists and gutters to the walls of buildings. As at present carried out it involves first securing a wooden wall- or frame-plate to the top of the building wall. In the case of masonry walls, the wooden wall-plate is bolted to the wall by means of anchor bolts that are usually built into the top portion of the wall at regular intervals by the mason. It requires careful marking and drilling to produce holes in the wooden wall-plate through which these anchor bolts will pass, when the plate is placed on top of the wall. The roof rafters and ceiling joists are then secured to the wall-plate by toe-nailing them thereon. The roof rafters are notched to provide a bearing surface on the wall-plate. Gutter straps are usually attached to the roof rafters at intervals to support a separate gutter. It is customary, in case of an overhanging roof, to provide a wooden cornice covering the ends of the roof rafters. All of these operations require considerable skilled labor. Furthermore, the toe-nailing of the rafters and joists does not furnish a very secure hold, so that there is some danger in wind storms and hurricanes that the roof may be torn from the building. This is most apt to occur when the atmospheric pressure outside the building becomes much lower than that within it.

It is the primary object of my invention to provide simple means for securing these various building elements, which may be installed with a minimum employment of skilled labor. Another object is to provide means to hold the roof rafters and ceiling joists to the building walls so firmly as to greatly lessen the danger that a wind storm or hurricane might unroof the building. Another object is to furnish means for firmly attaching the gutter to the top of the building wall, so that the gutter can never sag while allowing for easy replacement of any dam-

aged or rusted sections thereof. Another object is to eliminate plaster cracks that are caused by settling of the ceiling joists due to warping of the wooden wall-plates. Such warping frequently occurs, particularly when the wall-plate is made of wood that has not been properly seasoned. Further objects will be apparent from the following detailed description.

Referring to the drawings which are for illustrative purposes only:

Fig. 1 is a cross section of a building construction embodying the novel means referred to above.

Fig. 2 is a plan view of the wall-plate with the gutter, roof rafters and ceiling joists attached.

Fig. 3 is a perspective view of a cleat used for fastening the rafters and joists to the wall-plate.

Fig. 4 is a perspective view of an alternative form of cleat made of heavy gauge steel wire. While not as strong as the form shown in Fig. 3, it is much cheaper and will usually suffice, particularly where the roof rafters and ceiling joists occur singly.

Fig. 5 is a cross section along the line A—A' of Fig. 1, showing how a rafter and a joist may be secured to a pair of cleats and to each other whenever they occur together.

Fig. 6 is a perspective view of an anchoring saddle which serves to firmly hold the wall-plate to the top of the wall and thereby secure the cleats, when the nut on the anchoring bolt is tightened.

More particularly, describing the invention with reference to the drawings in which like reference numerals are used to indicate corresponding parts throughout the several views:

Reference numeral 1 generally indicates my new wall-plate which in the form illustrated is in the shape of an L, and which is preferably made of steel that has been rendered rust proof, for example, copper bearing steel or the like. The dimensions of the wall-plate may vary within wide limits, depending upon the type and size of building in which it is to be employed. Merely by way of example, it may be about $\frac{1}{4}$ inch thick and be supplied in eight-foot lengths. The height of its vertical portion may be varied widely. This will depend somewhat on the desired depth of the gutter and need only be sufficient to afford ample bearing surface for the vertical ends of the roof rafters. The width of its horizontal portion may likewise vary within wide limits. It must be sufficient to provide ample bearing surface for the horizontal ends of the roof rafters and for the ends of the ceiling

joists. Generally it will be wide enough to cover most of the top of the building wall.

Instead of being L-shaped, as shown, the wall-plate may, if desired, be T-shaped, i. e., part of its vertical portion may extend below the horizontal portion. All that is necessary is that it possess both a vertical and a horizontal portion, and that at least part of the vertical portion extend above the horizontal portion, thus providing a right-angled seat for the ends of the roof rafters.

The horizontal portion of the wall-plate is provided with apertures or slots 2 that may be approximately one-half the width of that portion and are of considerable length. The length of these apertures is limited by the required rigidity of the structure. Generally speaking, it is desirable to make them as long as is compatible with that requirement. These apertures serve a variety of purposes. In the first place they provide openings large enough so that the plate may be readily set down over the anchor bolts 3 that have been built into the top of the wall as usual by the mason, without any exact measuring or drilling, thus saving considerable labor. They also provide openings through which the vertical portions of the adjustable cleats 4 extend at desired intervals. Finally they serve to lighten the structure and conserve material.

It will be noted that at the longer edges of the apertures or slots the wall-plate is reduced in thickness, providing recesses 19 running the full lengths of the apertures to accommodate the ends of the horizontal portions of the cleats 4. The vertical portion of the wall-plate is provided with means for attaching the gutter 5 thereto. These means may consist of threaded holes 6 at suitable intervals for the insertion of tap screws 7, as shown in Fig. 1. Preferably these holes are located high enough to be above the water level of the gutter.

The gutter 5 may be of any convenient shape and is suitably furnished in lengths equal to those of the wall-plate. When first installed, the gutter and wall-plate may come assembled and be furnished as a unit. The gutter is provided with corresponding holes for insertion of the cap screws 7. Some of the gutter sections may be provided with a hole 8 for insertion of a drain pipe or leader 9. The gutter is also provided with end or return pieces 20 to give the proper architectural effect on the end walls of the building without the necessity of finished carpentry work to accomplish this result. As shown in Fig. 1, the vertical portion of the gutter, which is attached to the vertical portion of the wall-plate, preferably extends somewhat below the horizontal portion of the plate, so that the gutter serves to seal the joint between the horizontal portion of the wall-plate and the top of the building wall 10 against the entrance of moisture.

The adjustable cleats 4 which are shown in detail in Figs. 3, 4 and 5, are right-angled, metal brackets in which the horizontal portion is of greater length than the parallel dimension of the vertical portion, thus affording ends which are to be held under the wall-plate in the recesses along the apertures therein. The said parallel dimension of the vertical portion and the width of the horizontal portion must be less than the width of the apertures in the wall-plate to permit insertion of the cleats through the apertures during installation. The vertical portion of the cleats is provided with a suitable number of holes or a slot 11 through which nails 12 may be driven

into the roof rafters 13 and ceiling joists 14, as shown, for example, in Fig. 5. The form of cleat shown in Fig. 4 may be modified by locating the ends of the wire of which the cleat is made at the top of the vertical portion, bending both ends of the wire in a direction parallel to and away from the horizontal portion, and pointing the said ends. These pointed ends can then substitute for the nails indicated in Fig. 4.

The means for fastening the wall-plate to the top of the building wall include the anchoring bolts 3 and anchoring saddles 15, one of which is shown in detail in Fig. 6. The anchoring saddles are of greater length than the width of the apertures in the wall-plate, so that they extend over both sides of the apertures and serve to securely hold down the wall-plate, when the nut 16 is tightened on the anchoring bolt 3. If desired, a washer 17 is provided between the anchoring saddle and the nut.

The method of installing my new wall-plate and of attaching the various building elements thereto is as follows:

The building wall 10, which may be of brick as shown in Fig. 1 or of stone, concrete or any other building material, is brought up to its proper height with built-in anchor bolts 3 at suitable intervals, for example, every 4 or 5 feet. In the case of brick or stone, a thin cement bed 18 is then trowelled on top of the wall to provide a level bearing surface. Then the wall-plate 1 is laid on top of the wall with the anchor bolts extending through the apertures 2 in its horizontal portion. The vertical portion of the wall-plate is usually, but not necessarily, located flush with the exterior of the building wall, as shown in Fig. 1. The anchoring saddles 15 are then placed over the anchoring bolts 3, as are the washers 17 and the nuts 16. Before tightening the nuts, the desired number of cleats 4 are inserted through the apertures in the horizontal portion of the wall-plate. This is possible, because the width of the horizontal portion of each cleat is less than the width of the apertures in the wall-plate. After insertion each cleat is turned at right angles to assume the position shown in Fig. 1, whereby the ends of its horizontal portion are accommodated by the recesses 19 in the under-surface of the wall-plate on both sides of the apertures. It is also possible, where the required number of cleats is known beforehand, to insert the vertical portions of the cleats through the bottom of the wall-plate before laying down the latter, in which case the horizontal portions of the cleats can be wider than the apertures.

The cleats are then adjusted to their proper positions as shown in Fig. 2, i. e., to positions adjoining each of the roof rafters and joists. While it is customary to provide such rafters and joists at regular intervals, it is sometimes necessary to do so at irregular intervals, in case a chimney, a dormer window, or the like interferes. The length of the apertures in the wall-plate makes it possible to adjust the positions of the cleats to take care of any such irregularities.

Once the cleats have been set up in the desired positions, the nuts on the anchoring bolts may be tightened to hold them there. Then the ceiling joists and roof rafters are nailed to the vertical portions of the cleats, as shown in Figs. 1, 2 and 5 of the drawings. The ends of the roof rafters are firmly seated within the right angle formed by the wall-plate, and any lateral force exerted by the rafters is taken up by the vertical

portion of the wall-plate. The cleats eliminate the necessity of toe-nailing the roof rafters and ceiling joists, and the entire assembly provides a very secure joint between the roof, ceiling and building wall.

For the original installation it is preferable that the gutter and the wall-plate be furnished already assembled. Conceivably they might be furnished in a single piece, but this would not be practical, because the wall-plate becomes an integral part of the building and could not be removed, in case the gutter must be replaced due to corrosion or some other injury. It is, therefore, desirable that the gutter be readily removable for replacement, as in the structure shown in Figs. 1 and 2. The joints between the gutter sections may be sealed with a caulking compound as shown at 21 in Fig. 2.

My new wall-plate provides a very convenient means for firmly attaching the gutter. The gutter is securely held so that it can never sag, and yet it can be readily replaced. It is possible to thus provide not only a very efficient gutter construction, but also one that is quite pleasing in appearance.

It is obvious that many variations from the specific construction herein illustrated and described may be made without departing from the scope of my invention. Such variations and modifications will readily occur to those skilled in the art. I, therefore, do not limit myself to the particular forms herein described, but intend to cover all such variations and modifications as are embraced within my claims.

I claim:

1. A wall-plate for securing various building elements at the top of a building wall, said wall-plate being many times as long as it is wide and having a horizontal portion adapted to seat on the top of the building wall and a vertical portion extending at least in part above said horizontal portion thus forming an angled, roof rafter seat, the said horizontal portion being provided with elongated apertures for receiving means to secure the wall-plate to the top of the building wall and means to secure the roof rafters and ceiling joists of the building to the wall-plate, and the said vertical portion including means to secure a gutter thereto.

2. A metal wall-plate for securing various building elements at the top of a building wall, said wall-plate being many times as long as it is wide and, when installed, having a horizontal portion seating on the top of the building wall and a vertical portion facing the exterior of the building and extending above said horizontal portion, thus forming an angled, roof rafter seat, the said horizontal portion being provided with elongated apertures through which anchoring bolts are passed to secure the wall-plate to the top of the building wall and through which cleats are inserted to in turn secure the roof rafters and ceiling joists of the building to the wall-plate, and the said vertical portion including holes by means of which a gutter may be secured thereto.

3. A metal wall-plate, as claimed in claim 2, having recessed portions underneath the full

length of the longer edges of the apertures to accommodate those parts of the cleats that lie beneath the wall-plate.

4. Means for securing the roof rafters and ceiling joists to the top of a building wall, comprising a gutter and a wall-plate, each of substantially equal length, joined together side by side in a manner permitting ready replacement of the gutter, the said wall-plate having a horizontal portion adapted to seat on the top of the building wall and a vertical portion extending at least in part above said horizontal portion, thus forming an angled, roof rafter seat, the said horizontal portion being provided with elongated apertures for receiving means to secure the wall-plate to the top of the building wall and means to secure the roof rafters and ceiling joists to the wall-plate.

5. Means for securing roof rafters and ceiling joists to the top of a building wall, comprising a gutter and a metal wall-plate, each of substantially equal length, joined together side by side in a manner permitting ready replacement of the gutter, the said wall-plate, when installed, having a horizontal portion adapted to seat on the top of the building wall and a vertical portion to which the gutter is joined facing the exterior of the building and extending above the horizontal portion, thus forming an angled, roof rafter seat, the said horizontal portion being provided with elongated apertures through which anchoring bolts are passed to secure the wall-plate to the top of the building wall and through which cleats are inserted to in turn secure the roof rafters and ceiling joists to the wall-plate.

6. Securing means, as claimed in claim 5, having recessed portions underneath the full length of the longer edges of the apertures to accommodate those parts of the cleats that lie beneath the wall-plate.

7. Means for securing roof rafters and ceiling joists to the top of a building wall, comprising a gutter, a wall-plate and cleats, the gutter and wall-plate being of substantially equal length and joined together side by side in a manner permitting ready replacement of the gutter, the said wall-plate having a horizontal portion adapted to seat on the top of the building wall and a vertical portion to which the gutter is joined, extending at least in part above the horizontal portion, thus forming an angled, roof rafter seat, the said horizontal portion being provided with elongated apertures for receiving means to secure the wall-plate to the top of the building wall, and the said cleats having horizontal portions adapted to seat on the top of the building wall beneath the horizontal portion of the wall-plate, and vertical portions adapted to extend through the apertures of the wall-plate and to be secured to the roof rafters and ceiling joists when seated on the wall.

8. Securing means, as claimed in claim 7, having recessed portions underneath the full length of the longer edges of the apertures, adapted to receive those parts of the horizontal portions of the cleats that lie between the wall-plate and the top of the building wall.

E. WILLIAM MARTIN.
